Primary Examiner — Kevin K Rudzinski*Assistant Examiner* — Richard E Yenchesky(57) **CLAIM**

The ornamental design for dish rack, as shown and described.

DESCRIPTION

1. Dish rack
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Unfolded

Fig. 1.9 is an enlarged partial view taken from the corner shown in fig. 1.1 and fig. 1.10 is a perspective view of the dish rack where the dish rack is in a configuration of use.

(Continued)

The broken lines in the drawings depict portions of the dish rack that form no part of the claimed design.

1 Claim, 10 Drawing Sheets
